(Granted under Title 35, U. S. Code (1952),
sec. 266)

1

This invention relates to ordnance fire control and more particularly to a novel method and apparatus for use in directing a torpedo from a moving craft to a target. The present invention is characterized by its use, in a new manner, of the principle that when a torpedo is released on a sight line to a target and on a bearing having a torpedo velocity component perpendicular to the sight line and equal to and in the same direction as the target velocity component perpendicular to the sight line, with the torpedo and target having a net component of velocity toward each other, the torpedo will effect a collision with the target.

For illustrative purposes, the invention will be described in connection with a method and apparatus for directing a torpedo from an air-craft to a target, although it will be understood that the invention may be used on other types of crafts, such as surface and subsurface craft.

One object of the present invention resides in the provision of a method and apparatus for use in directing a torpedo from a moving craft to a target, in which the torpedo bearing and torpedo release point necessary to effect a torpedo hit on the target are computed quickly and accurately.

Another object of the invention is to provide a method and apparatus of the character described which is particularly adapted for use on an air-craft against a moving target.

Still another object is to provide a method and apparatus of the character described which permit a wide latitude for maneuvering of the attacking craft after computation of the necessary torpedo bearing and release point and prior to release of the torpedo, whereby the attacking craft is less vulnerable to counter-action from the target.

An additional object is to provide an apparatus of the character described in which the computations require only a few manual operations.

A further object is to provide an apparatus of the character described which may be made in a compact form of relatively simple construction.

Still another object is to provide a method and apparatus of the character described in which a sight line is established from the attacking craft to the target, preferably by a directionally stabilized sight, and the sight is adjusted in train, partly automatically and partly manually, to maintain the target in the vertical center of the sight during the attacking run, whereby the torpedo bearing and torpedo release point necessary to hit the target are automatically computed.

In accordance with the invention, an original

2

sight line is established to the target, preferably by training upon the target a directionally stabilized sight. The velocity component of the attacking craft perpendicular to this sight line is continuously computed, and from this velocity component a correction factor is subtracted representing the velocity component of the target perpendicular to the sight line. The remainder of these two components is multiplied by time to provide a continuous indication of the displacement of the attacking craft from a sight line through the target and parallel to the original sight line. The sight is rotated in train through an angle whose sine is a function of this displacement, the above noted correction factor being adjusted manually to maintain the target image against azimuth displacement in the sight. This adjusted correction factor is utilized in computing the torpedo bearing necessary to provide a torpedo velocity component perpendicular to the sight line and equal to and in the same direction as the target velocity component represented by the correction factor when the target image is maintained in the vertical center of the sight.

Thus, when the torpedo is released on the computed torpedo bearing to cause the torpedo to enter the water at zero displacement as represented by the displacement indication, the torpedo will effect a collision with the target.

These and other objects of the invention may be understood by reference to the following detailed description in conjunction with the accompanying drawing illustrating schematically an apparatus made in accordance with the invention.

The present invention is based upon the fact that if a target maintains its image in the vertical center of a directionally stabilized sight, the sight and the target must both have the same component of velocity in the same direction perpendicular to the line of sight. If the sight and the target also have a net component of velocity toward each other, the two will eventually collide.

According to the invention, the component of the air velocity of the aircraft perpendicular to the sight line is computed by multiplying the true air speed of the craft by the sine of the included angle between the sight line and the direction of the aircraft heading. The component of the wind velocity perpendicular to the sight line is also computed by multiplying the wind speed by the sine of the included angle between the sight line and the wind direction. These two computed components are added algebraically

to obtain the component of ground velocity of the aircraft perpendicular to the sight line, the output of this algebraic addition being a member which moves at a rate directly proportional to, and in a direction corresponding to, the aircraft's component of ground velocity perpendicular to the sight line.

If the components of aircraft ground velocity and target velocity perpendicular to the line of sight are equal and in the same direction, the target image will remain in the vertical center of the sight. However, if these components of aircraft ground velocity and target velocity are unequal the apparatus can maintain the target in the vertical center of the sight by either of two methods, one of which in effect displaces the sight in a direction parallel to itself and perpendicular to the original sight line without changing the sight bearing, and by an amount equal to the displacement of the aircraft from the sight line, and the other of which rotates the sight in train through an angle whose sine is a function of the aircraft's displacement from the sight line. It will be understood that "sight line" is intended to denote the line of sight, parallel to the original sight line, and passing through the target. Thus, the sight line may be moving or stationary, depending upon whether the target has a velocity component perpendicular to the sight line.

It will be apparent that it is impracticable to employ the first method to maintain the target image in the vertical center of the sight, in view of the limited amount by which the sight may be displaced on the aircraft without changing the sight bearing. Accordingly, the second method outlined above is utilized in the preferred practice of the invention. To this end, the computer element which moves at a rate directly proportional to the aircraft component of ground velocity perpendicular to the sight line is associated with an adjustable correction device which subtracts from this rate a rate proportional to the target velocity component in the same direction perpendicular to the sight line, so that if these two components are algebraically equal the output of the correction device is zero. A displacement indicator is operatively connected to the output end of the correction device, so that change of the displacement indicator is zero when the aircraft and the target have equal components of ground velocity in the same direction perpendicular to the sight line. If these two components are unequal, the output of the correction device corresponds in direction and is proportional in rate to the direction and rate, respectively, of the displacement of the aircraft from the sight line, that is, from a sight line to the target and parallel to the original sight line. The displacement indicator actually multiplies the output rate of the correction device by time so that the reading of the indicator can be calibrated directly in miles or other unit of displacement perpendicular to the sight line.

The displacement of the aircraft from the sight line and the range from the aircraft to the target are the two functions which determine the angle through which the sight should be rotated in train on its stabilized bearing so that the target image will remain in the vertical center of the sight even though the aircraft is displaced from the sight line. Thus, regardless of any maneuvers or change in the air speed of the aircraft, the target image will remain in the vertical center of the stabilized sight as long as the target does

not change its speed or heading. If the target maneuvers, its image will begin to creep from the vertical center of the sight, and thus the amount of correction (in terms of velocity) which must be subtracted by the adjustable correction device from the component of aircraft ground velocity perpendicular to the sight line must be either increased or decreased, depending upon whether the target has increased or decreased its velocity perpendicular to the sight line. This in effect controls the velocity of the sight line so that it always passes through the center of the target and thus must travel with the same component of velocity perpendicular to the sight line. Accordingly, whenever the target image remains in the center of the sight, the velocity of the above correction factor is proportional to the component of velocity of the target perpendicular to the sight line.

If the torpedo is released on the sight line, as defined above, with its component of velocity perpendicular to the sight line equal to and in the same direction as the target velocity component perpendicular to the sight line, and with the torpedo headed in the general direction of the target, the two will collide. In accordance with the invention, the torpedo heading or bearing necessary to effect this collision is computed, in effect, by rotating a vector equal in length to the torpedo speed until its velocity component perpendicular to the sight line is equal to the target velocity component perpendicular to the sight line, and with the torpedo headed in the general direction of the target, the final position of the vector representing the necessary torpedo bearing.

The torpedo must hit the water on the sight line, as defined above, in order that its component of velocity perpendicular to the sight line will be equal to the target component of velocity perpendicular to the sight line. When the aircraft is approaching the sight line at the instant of torpedo release, the release must be effected before the aircraft reaches the sight line, if the torpedo is to enter the water on the sight line. It will be apparent that this necessary "lead" will be a function of the aircraft's altitude and its rate of approach to the sight line at the instant of release. According to the present invention, after the necessary torpedo bearing is computed as described above, the aircraft is maneuvered to cause it to approach the sight line, and the rate of this approach is determined by measuring the rate of approach of the displacement indicator toward zero. The altitude of the aircraft above the water, being a direct function of time, can be converted into the time of fall of the torpedo from that altitude. This time factor is multiplied by the rate of approach of the aircraft toward zero displacement, as computed from the displacement indicator, so that the result is the displacement of the aircraft from the sight line at which the torpedo should be released to cause it to enter the water on the sight line. By subtracting from the reading of the displacement indicator the value representing the product of the above multiplication, the torpedo when released at zero displacement (as represented by the modified indicator reading) will hit the water just as it crosses the sight line.

Referring now to the drawing, numeral 8 designates a standard compass repeater unit which is energized by the usual gyro fluxgate compass (not shown) on the aircraft. The compass repeater 8 provides in effect a fixed magnetic reference bearing, so that the output end of the re-

repeater 8 moves in accordance with changes in the heading of the aircraft. The output end of the compass repeater 8 is connected through gearing 3 and shaft 10 to one side of a differential 11. The output shaft 11a of the differential is connected to one side of a differential 12 having its output end connected through a shaft 13 and bevel gearing 14 to an optical sight 15. The shaft 13, gearing 14 and sight 15 are supported on a suitable mount (not shown) which is stabilized in roll and pitch. The sight 15 may be of any standard type and has the usual vertical hair line at the center of the sight, the sight being movable in train on its stabilized mount.

The sight 15 may be trained on the target by a sight bearing knob 16 connected through a shaft 16a to a gear 16b forming one of the input sides of a differential 17. The gear 16b operates through a shaft 18 and gearing 18a to drive the other input side of differential 11, that is, the side of the differential 11 opposite that which is driven from the compass repeater unit 8. Thus, the sight adjustment knob 16 serves to adjust the sight 15 in train relative to the directionally stabilized reference provided by the compass repeater unit 8, whereby any changes in the heading of the aircraft are compensated by the compass unit 8 through differential 11 to maintain the sight 15 on the sight bearing to which it was adjusted by knob 16. In other words, the sight 15 is directionally stabilized by the compass repeater 8.

The output shaft 11a of differential 11 is also connected through friction gearing 20 to a sine mechanism comprising a friction disk 21 driven by the gearing 20 and having near its periphery a pin 21a engaged in an elongated slot in a T-head 22. The stem 22a of the T-head is in line with the axis of rotation of the sine friction disk 21 and is suitably guided against lateral displacement. At its lower end, the stem 22a carries a cage 23 containing a pair of balls 24 disposed between a disc 25 and a roller 26. The disc 25 is driven by a shaft 25a rotated at a speed proportional to the true air speed of the aircraft, as by means of a standard "Pioneer air mileage unit" (not shown). The latter is actually used as a source of power and drives the disc 25 at a speed proportional of the true air speed of the aircraft. This disc 25 and roller 26 are separated by a distance equal to the sum of the diameters of the two balls 24, which are equal in diameter, and are spring loaded against each other through the balls 24.

The disc, balls and roller 25, 24 and 26 form a variable speed transmission or integrator. When the disc 25 is driven and the balls 24 are not at the center of the disc, the ball loaded against the disc will rotate and transmit the rotation through the second ball to the roller 26. Up to a certain limit, the magnitude of the spring loading will determine the tractive effort which the unit will transmit. The translation of the balls 24 by the stem 22a is restricted to a path parallel to the axis of roller 26, which is of a length equal to the diameter of the disc. Two balls 24 are used so that this translation can take place without skidding the balls on the disc or roller. If the balls 24 are positioned at the center of disc 25 by the sine mechanism, no rotation will be transmitted to the roller, but if the balls are positioned at the edge of disc 25 the roller will be driven at the maximum possible speed for the unit. The maximum speed is determined by the speed of rotation of the disc 25 and by the ratio

of diameters of the disc and the roller. Intermediate speeds of rotation of the roller 26 are obtained in direct proportion to the displacement of the balls 24 from the center of the disc.

It will be understood that the sine disk 21 will be rotated by differential 11 through an angle representing the included angle between the sight bearing, as determined by adjustment of knob 16, and the heading of the aircraft, as determined by the compass repeater 8. Thus, when the axis of sight 15 is parallel to the longitudinal axis of the aircraft (heading), the sine disk 21 will be in the zero position shown, with the pin 21a in line with stem 22a. However, when the heading of the aircraft is offset from the sight line, the sine disk 21 will be rotated through an angle equal to the angle of this offset, so that the balls 24 are displaced from the center of disc 25 through a distance proportional to the sine of this offset angle. The differential 11 drives the sine disk 21 with a one to one ratio with heading (compass repeater 8) and sight bearing (knob 16).

The angular velocity of roller 26 is equal to the product of the angular velocity of integrator disc 25 times the displacement of integrator balls 24. Thus, the angular velocity of roller 26 is directly proportional to the product of air speed times the sine of the included angle between the bearing of sight 15 and the heading of the aircraft; that is, the output of roller 26 is an angular velocity proportional to the component of air speed perpendicular to the sight line.

The component of the wind velocity perpendicular to the sight line is equal to the product of the wind speed times the sine of the included angle between the sight bearing and the wind direction. The wind speed is obtained from a variable speed transmission which receives its power from a constant speed driving disc 28. The variable speed transmission also includes a roller 29 and balls 30 mounted in a cage 31, the transmission being similar to the transmission 24, 25 and 26 previously described. A wind speed knob 32 is operable through a pinion 33 and rack 34 to adjust a shaft 35 connected to the cage 31. The knob 32 is calibrated directly in terms of wind speed so that the displacement of the balls 30 from the center of disc 28 is directly proportional to the wind speed. Thus, the roller 29 is driven at an angular speed directly proportional to the wind speed. The roller 29 is connected through bevel gearing 36 to a disc 37 forming part of another integrator or variable speed transmission to be referred to in greater detail presently.

A wind direction knob 40 is connected through a gear 41 to the other side of differential 17, that is, the side opposite the sight bearing gear 16b. The output end of differential 17 is connected through friction gearing 42 to a sine disk 43 having a pin 43a disposed in an elongated slot in a T-head 44, the stem 45 of the T-head being guided against lateral displacement. The T-head 44, sine disk 43 and pin 43a form a sine mechanism similar to that previously described. The stem 45 is connected to a cage 46 containing a pair of integrator balls 47 engaged between disc 37 and a roller 48. Since the wind direction and sight bearing are passed through differential 17 in opposite directions from knobs 40 and 16, respectively, the output of differential 17 is equal to the difference of the two, which is the included angle between the sight bearing and the wind direction. Accordingly, the sine mechanism 43 displaces the integrator balls 47 from the center of

disc 37 through an amount directly proportional to the sine of the included angle between the sight bearing and the wind direction. The output of the integrator 37, 47 and 48 is equal to the product of the rotational speed of disc 37 times the displacement of balls 47 from the center of the disc, which is equal to the product of the wind speed times the sine of the included angle between the sight bearing and the wind direction. Thus, the roller 48 rotates at a speed proportional to the component of the wind velocity perpendicular to the sight line and in a direction dependent upon the direction of this component relative to the sight line.

The component of ground speed of the aircraft perpendicular to the line of sight is obtained by algebraically adding the components of air velocity and wind velocity previously obtained as described above. The two rollers 26 and 48 rotate with angular velocities proportional to the components of aircraft air velocity and wind velocity, respectively, perpendicular to the sight line. These rollers 26 and 48 are connected to opposite sides of a differential 50 so that the two angular velocities are passed through the differential with such directions of rotation that the output of differential 50 is equal to the algebraic sum of the two components. Accordingly, the output shaft 51 of differential 50 rotates at a speed proportional to, and in a direction corresponding to, the component of aircraft ground speed perpendicular to the sight line.

A torpedo bearing indicator 52 is provided to indicate the true bearing on which the torpedo should be launched to effect a collision with the target. This bearing is obtained, in effect, by rotating a vector whose length is proportional to the torpedo speed, until the component of torpedo velocity perpendicular to the sight line is equal to and in the same direction as the target component of velocity perpendicular to the sight line. The component of torpedo speed is used to rotate the sight 15 at such a rate that the target image remains in the center of the sight. At this time, the components of torpedo speed and target speed perpendicular to the sight line are equal. The component of the torpedo speed perpendicular to the sight line is determined by multiplying the torpedo speed by the sine of the torpedo angle, which is the included angle between the sight bearing and the torpedo bearing.

The torpedo speed is set into the computor by driving an integrator disc 54 at an angular velocity proportional to the known torpedo speed. The torpedo angle is set in manually by a knob 55 which operates through bevel gear 55a to rotate a sine gear 56 through the same angle. The sine gear 56 forms part of a sine mechanism 56a, 57 and 58 similar to the sine mechanism 21, 21a and 22 previously described. The stem 58 of the sine mechanism is connected to a cage 59 containing integrator balls 60 engaged between the disc 54 and a roller 61. Rotation of the sine mechanism 56 thus displaces the integrator balls 60 from the center of disc 54 through an amount directly proportional to the sine of the torpedo angle as set in by knob 55. The output of the integrator or variable speed transmission 54, 60, 61 is equal to the product of the torpedo speed times the sine of the torpedo angle. Accordingly, the roller 61 has an angular speed proportional to the component of the torpedo velocity perpendicular to the sight line. If the target's image remains stationary in the sight 15, the output of roller 61 is also proportional to

70
75

the component of the target velocity perpendicular to the sight line. Under this condition, the angle of rotation of sine mechanism 56 is equal to the torpedo angle.

5 The angular displacement (torpedo angle) of sine mechanism 56 is passed through a gear train 63, 64 to one side of a differential 65, the other side of the differential being connected through a gear 66 to the shaft 16a operated by the sight bearing knob 16. The output end of differential 65 is connected to the torpedo bearing indicator 52. It will be apparent that the sight bearing fed by knob 16 into the differential 65 is displaced by knob 55 through gearing 63, 64 by an angle equal to the torpedo angle, so that the output from differential 65, as shown on indicator 52, is equal to the torpedo bearing.

The components of the aircraft ground velocity and target ground velocity perpendicular to the sight line are subtracted in order to obtain the ground velocity of the aircraft relative to the target in a direction perpendicular to the sight line, that is, to obtain the aircraft's component of ground velocity perpendicular to a sight line to the target and parallel to the original sight line established by adjustment of knob 16. The output of differential 50, which is an angular velocity proportional to the aircraft's component of ground velocity perpendicular to the sight line, and the output of roller 61, which is an angular velocity proportional to the target's component of velocity perpendicular to the sight line, are the two inputs to a differential 68. The output of differential 68 is therefore an angular velocity directly proportional in magnitude, and corresponding in direction, to the aircraft component of velocity perpendicular to the moving sight line to the target, which is the rate of displacement of the aircraft from the moving sight line to the target. (It will be understood that "moving sight line" is intended to denote a sight line to the target and parallel to the original sight line established by sight 15. Thus, the "moving sight line" may be moving or stationary depending upon whether the target has a velocity component perpendicular to the sight line.) If the angular velocity of the output of differential 68 is proportional to this rate of displacement of the aircraft from the moving sight line, the total number of revolutions of the output end of differential 68 is proportional to the total displacement of the aircraft from the moving sight line.

The output end of differential 68 is connected through a shaft 69, worm 70 and worm wheel 71 to a displacement indicator 72. The displacement indicator is in effect a revolution counter calibrated in miles or other unit of displacement. It comprises a pointer 73 which rotates with the shaft 71a on which wheel 71 is mounted. The pointer 73 cooperates with a scale 74 in the form of a sector plate loosely mounted on shaft 71a, the plate being suitably calibrated in terms of displacement to the right or left of a zero position (moving sight line). On its periphery the plate 74 has teeth 75 which mesh with a worm 76 mounted on a shaft 77, for a purpose to be described presently. The worm and wheel 70, 71 provide a large gear reduction so that a large number of revolutions of output shaft 69 is required to move the pointer 73 through a relatively small angle.

The output shaft 69 of differential 68 also operates through bevel gears 80 to drive a lead screw 81 which is threaded through a cage 82

containing the balls 83 of an integrator 84, 85 similar to the integrator previously described. The input to the integrator disc 84 is obtained from a constant speed motor drive. By reason of the lead screw 81, the integrator balls 83 are displaced from the center of disc 84 through an amount directly proportional to the aircraft's displacement from the moving sight line, as determined by the output of differential 68. Thus, the angular velocity of roller 85 is directly proportional to the displacement of the aircraft from the moving sight line.

An integrator disc 87, driven at constant speed, engages one of a pair of integrator balls 88 in a cage 90. The other ball 89 engages a roller 91, the disc, balls and roller 87, 89, 91 forming a variable speed transmission similar to those previously described. The cage 90 is connected to a rack 92 movable by a pinion 93 which may be rotated by a range knob 94. Thus, the integrator balls 88 are displaced from the center of disc 87 by an amount proportional to the range to the target, as set in by knob 94. The output roller 91 rotates at a speed proportional to a constant times the range and is connected through bevel gearing 96 to an integrator disc 97 which, therefore, also rotates at a speed directly proportional to the range. The disc 97 forms part of a similar variable speed transmission 98, 99 and 100, the cage 99 being connected to a stem 101 of a sine mechanism 102, 102a and 103 similar to the sine mechanism previously described. The integrator balls 98 are thus displaced from the center of disc 97 by an amount proportional to the sine of the angle of rotation of sine friction disk 102.

The integrator roller 100 assumes an angular velocity proportional to the product of the range times the sine of the angle of rotation of the sine disk 102. The outputs of the two rollers 85 and 100 are geared to the two input sides, respectively, of a differential 105, the roller 85 being connected to differential 105 through gearing 106, and the roller 100 being connected to the differential through a bevel gear 107. The output of differential 105 is connected through a friction disk train 108 to the sine disk 102. The output rate of roller 85 is proportional to the airplane's total displacement from the moving sight line, and the differential 105 subtracts the output from the two rollers 85 and 100 so that if the two are equal the differential will have no output. If the two are unequal, the output of differential 105 drives the sine mechanism 102 which displaces the integrator balls 98 to a point where the roller 100 has the same angular velocity as roller 85, which is proportional to the displacement of the airplane from the moving sight line. The angular velocity of roller 100 is equal to the product of the angular velocity of the integrator disc 97 times the displacement of the balls 98, or the angular displacement rate of roller 100 is proportional to the range times the sine of the angle of rotation of sine mechanism 102. This can be expressed in the equation

$$\text{sine } \theta = \frac{\text{Displacement of airplane from moving sight line}}{\text{Range}}$$

and θ is the angle through which the sight 15 must be offset so that the target will remain in the center of the sight even though the airplane is not on the moving sight line. The angle θ is the angle of rotation of the sine mechanism 102, and that rotation is transmitted through a gear

train 110 to the other input side of differential 12 where it is combined with the sight bearing from differential 11. The output of differential 12 is the algebraic sum of the two inputs, and this output, as previously described, controls the magnetic bearing which the sight 15 assumes.

As pointed out in greater detail hereinafter, the torpedo is released to cause it to enter the water on the moving sight line, that is, on zero displacement as indicated by indicator 72. The instant of torpedo release necessary to accomplish this is a function of the product of the altitude of the aircraft times the rate of approach of the aircraft to the moving sight line. The output 69 of differential 68 has an angular velocity directly proportional to the rate of the airplane displacement from or approach to the moving sight line. An integrator unit converts the angular velocity of shaft 69 to an angular displacement directly proportional to the rate of the airplane displacement from or approach to the moving sight line. More particularly, the integrator unit comprises a constant speed disk 112 engaging one of a pair of integrator balls 113 mounted in a cage 114 on a screw spindle 115, the other ball 113 engaging a roller 116. The roller 116 is connected through gearing 117 to one side of a differential 118, the other side of which is driven from a gear 119 on shaft 69. At its output end, the differential 118 is connected to the screw spindle 115 which, when rotated, adjusts the position of integrator balls 113 on disk 112. It will be apparent that the angular velocity of shaft 69 and the angular velocity of output roller 116 are subtracted in the differential 118 so that the output of this differential is equal to the difference of the two values and controls the position of integrator balls 113. Since the integrator disk 112 is driven at constant speed, the output of integrator 112, 113 and 116 is directly proportional to the displacement of the balls 113. If the two inputs of differential 118 are unequal, the output of differential 118 will displace the balls 113 in such a direction and by such an amount that the output rate of roller 116 will approach equality with the rate of rotation of shaft 69, that is, the rate of the aircraft displacement from or approach to the moving sight line. Thus, whenever the system is in equilibrium, the linear displacement of the balls 113 will be directly proportional to the rate of displacement or approach of the airplane relative to the moving sight line, and also the output of differential 118 will have turned through a proportional number of revolutions in the process of displacing the balls 113. The rate of displacement is expressed in units of displacement per second, and the altitude can be expressed in the time of fall of the torpedo in seconds. Thus, when the two are multiplied the following equation results:

$$\frac{\text{displacement}}{\text{time}} \times \text{time} = \text{displacement}$$

This displacement will be in the same units that are calibrated on the displacement indicator 72. The linear displacement of the integrator balls 113 is multiplied by the time of fall of the torpedo by passing the angular displacement of the output of differential 118 through a gear train 120 whose ratio is proportional to the time of torpedo fall. It will be understood that the gear train 120 may be adjusted to provide a speed ratio corresponding to the predetermined altitude from which the torpedo is to be launched, that is, the predetermined time of fall of the torpedo. The

gear train 120 drives the shaft 77 which operates through worm 76 and teeth 75 to offset the dial 74 and move the zero position thereof a slight amount. When the torpedo is dropped from the aircraft at zero displacement, as represented on indicator 72, the torpedo will enter the water directly under the airplane at the instant that the airplane crosses the moving sight line, regardless of the altitude of the aircraft or the rate of its approach to the sight line.

In the operation of the torpedo director, the torpedo speed is set in when the torpedo is loaded into the plane, by adjusting the speed of disk 54. The altitude of torpedo drop is assumed by the pilot before the run, and the ratio of gear train 120 is adjusted to correspond to the time of fall from the desired altitude. If desired, however, the altitude can be set in continuously by employing a variable speed transmission between spindle 115 and shaft 77 and adjusting the transmission from a suitable altimeter. The wind velocity is set in to the unit manually by knob 32 calibrated in knots or other unit of velocity, and can be determined from the home base or by drift sight or approximation. The wind direction is set in manually by knob 49 having a dial (not shown) similar to a compass dial. The wind direction can be obtained from the home base or by drift sight or approximation. The range is set in by the range knob 94. This setting may be made on the basis of an estimated range, because the range has very little effect on the accuracy of the computer, since the torpedo is always released on the moving sight line where the angle of offset of which range is a function is zero.

When the aircraft is in flight and a target is sighted, the sight bearing knob 16 is adjusted to train the sight 15 on the target, so that the vertical hair line of the sight intersects the target. At the same time, the system is started in operation, with the displacement indicator 72 at zero, by starting the constant speed driving members 28, 54, 84, 87, and 112 and connecting the integrator disk 25 to the air mileage unit through a shaft 25a. If the target image in the sight 15 commences to creep to the right or left of the vertical hair line, the torpedo angle knob 55 is adjusted to cause the image to move back to the hair line and to be maintained on the hair line. As pointed out heretofore, when the target image remains on the vertical hair line of sight 15, the correction roller 61 is rotating at a rate proportional to the target velocity component perpendicular to the original sight line. When this condition is obtained, the torpedo bearing indicated on the indicator 52 is the true bearing on which the torpedo is to be released to effect a collision with the target. During the attacking run of the aircraft, the displacement indicator 72 continuously indicates the total displacement of the aircraft from the moving sight line, the rate of movement of pointer 73 indicating the rate of aircraft displacement from the moving sight line. When the system has been stabilized by adjustment of the torpedo angle knob 55 so that the target image remains in the vertical center of the sight, the airplane is maneuvered so as to cause displacement pointer 73 to move back toward the zero position on dial 74. When the pointer 73 reaches the zero position, the torpedo is released manually or automatically to cause it to enter the water at the moving sight line and on the torpedo bearing shown on indicator 52. It will be understood

that with ordinary torpedoes the aircraft must assume the torpedo bearing shown on indicator 52 before releasing the torpedo, but if a maneuverable torpedo is used the torpedo bearing can be stabilized in the torpedo so that the aircraft can assume any heading when the torpedo is released.

The new method and apparatus permit considerable maneuvering of the attacking craft during solution of the fire control problem and prior to release of the torpedo, so that the attacking craft is less vulnerable to defensive action. The method may be practiced with ease by the use of the new apparatus, and the invention provides an accurate solution of the torpedo bearing and dropping point to effect a hit on the target. It will be apparent that the apparatus may be readily adjusted to compensate for evasive maneuvers of the target prior to release of the torpedo, by manipulation of torpedo angle knob 55 to maintain the target image on the vertical center of the sight 15.

The invention herein described may be manufactured and used by or for the Government of the United States of America for governmental purposes without the payment of any royalties thereon or therefor.

I claim:

1. In an apparatus for use on a moving craft to direct a torpedo from the craft to a moving target the combination comprising a directionally stabilized member, a first differential having a manually settable input to set said member to a position parallel with an original line of sight from the craft to the target, computing means for moving the said member in train through an angle θ , said computing means including a first element rotatable at a rate proportional to the velocity component of the craft perpendicular to the original sight line, a second element rotatable at a rate proportional to the predetermined torpedo velocity, a third rotatable element, a speed varying member coupling said third element to said second element, angularly rotatable means for manually adjusting said speed varying member so that the rate of rotation of the third element is proportional to the torpedo velocity multiplied by the sine of the angle of rotation of said manually adjustable means, a fourth rotatable element, a source of constant speed, speed varying means for transmitting rotation from said source to said fourth element at a rate proportional to a displacement D corresponding to the integrated difference in rate of rotation of said first and third elements, means rotatable at a rate proportional to the range R from said craft to said target, a second differential means having as output feeding said first differential for positioning said directionally stabilized member in train through said angle θ determined by the difference in inputs to said respective differentials, a fifth rotatable element, means adjustable by the output of said differential means to drive said fifth element at a rate proportional to said range multiplied by the sine of the angle θ , said inputs to said differential means comprising said fourth and fifth rotatable elements whereby said differential output will be zero whose θ equals an angle whose sine is said range divided by said displacement, means positionable to an angle corresponding to the difference in manual setting of said member and said angularly rotatable means whereby to indicate the correct bearing angle at which said torpedo is to be released at zero displacement when said

angularly rotatable means is manually adjusted an amount to keep said member parallel to azimuth bearing line to said target.

2. The combination defined in claim 1 above characterized further by the addition thereto of an indicator for said displacement D having a pointer movable at a rate proportional to the difference in rate of said first and third elements whereby said pointer will be movable to a position corresponding to the integrated difference in rate of said first and third elements, a scale for said pointer and means for moving said scale in a direction opposite to the movement of said pointer at a rate proportional to said displacement multiplied by the time of fall of said torpedo from a predetermined altitude of said craft whereby upon release of said torpedo from said craft at a displacement $D=0$ as indicated

5 by said pointer on said dial, the torpedo will enter the water on the sight line having a bearing to said target such that the component of velocity of said torpedo normal to the sight line will equal the component of velocity of said target normal to said sight line.
